PUMP SHAKER

Marvin Johnston, Pampa, Tex., assignor, by direct and mesne assignments, to J. M. Huber Corporation, Borger, Tex., a corporation of New Jersey

Filed Mar. 27, 1961, Ser. No. 98,412
14 Claims. (Cl. 103—179)

This invention relates to oil well pumps and more particularly to a device for freeing a stuck valve of an oil well pump.

Much petroleum is produced by pumping it from deep within the ground. A typical operation includes a pump within the ground operated by a sucker rod from the surface of the ground. Often foreign material such as sand or paraffin gets in the pump causing a valve of the pump to stick in the open position. There are two possible methods of unsticking the valve. One is to pull the pump from the well and clear the valve at the top of the ground. The other is to shake or deliver an impact to the valve in situ. The second method is preferable if possible.

Various devices and procedures have been suggested for shaking the sucker rod to thus shake the valve in the pump. My invention is an improved device for this purpose.

My device operates by preventing the sucker rod from descending all the way to the bottom of the stroke by placing a stiff arm between a clamp on the polish rod and the stuffing box. The polish rod attaches to the top of the sucker rod and may be considered an extension thereof. Then when the reciprocating structure (horsehead and bridle) reach bottom dead center or there about, the stiff arm is removed allowing the full weight of the sucker rod to fall against its reciprocating structure. Generally this results in sufficient impact to shake the valve loose.

An object of this invention is to provide a device for shaking pumps deep within the earth.

Another object of this invention is to provide a device which may be operated by one man.

Another object is to provide a device which delivers a large impact.

Another object is to provide a device whereby the amount of impact is within the control of the operator.

A further object is to provide a device which is safe to operate.

A further object of this invention is to provide a device which will operate with any of several different manufacturers of polish rods and/or stuffing boxes.

Still further objects are to achieve the above with a device that is sturdy, compact, durable, simple, and reliable, yet inexpensive and easy to manufacture.

The specific nature of the invention as well as other objects, uses, and advantages thereof will clearly appear from the following description and from the accompanying drawing, the different views of which are not necessarily to the same scale, in which:

FIG. 1 is an elevational view of a device according to this invention as used on a well just before tripping.

FIG. 2 is an elevational view of the device after it has been tripped and the impact delivered.

FIG. 3 is a sectional view taken on line 3—3 of FIG. 2.

FIG. 3-A is the same as FIG. 3 limited to an enlarged detail of the bearing bolt.

FIG. 4 is a sectional view taken on line 4—4 of FIG. 1.

FIG. 4-A is the same as FIG. 4 limited to an enlarged detail of the detent.

FIG. 5 is a sectional view taken on line 5—5 of FIG. 3.

As may be seen in the accompanying drawing, an embodiment of this invention is intended to be attached to an oil well pump 8.

Piston 10 including valve 12 is located within pipe 14

2

deep within the ground. The piston 10 is operated by a sucker rod which extends from the piston to above the surface of the ground to polish rod 16. Adjacent the top of the polish rod 16 clamp 18 surrounds the polish rod 16 and acts as a stop for cross bar 20. The cross bar 20 is supported by cables 22 which depend from horsehead 24 which oscillates causing the cables 22 to have vertical reciprocal motion which is transferred through the cross bar 20 and clamp 18 to the polish rod 16 and sucker rod. Thus, means are provided to reciprocate the sucker rod. Stuffing box 28 is located at the top of the pipe 14 above the surface of the ground. It is means for forming a fluid tight seal between the pipe 14 and the polish rod 16. Somewhere below the stuffing box 28 outlet pipe 29 conveys the fluid pumped from the pump 8 to a place of storage.

All that has been specifically described above is conventional, the parts are already available on the market, and as such, form no part of this invention.

20 Clamp 30 clamps around the polish rod 16. This extension of the sucker rod is conventionally called a polish rod because of its polished surface which works through the stuffing box 28. The clamp 30 includes two portions with segmental cylindrical cavities 31 which are hinged

25 together at 32 and are clamped together by threaded bolt 34. The clamp 30 is quite similar to that conventional clamp 18 which forms a stop above the cross bar 20. One portion of the clamp 30 has ear 36 integral therewith. It will be understood that it could be welded to the clamp

30 30 as well as being made integral. The bottom portion of the ear 36 is bifurcated and has a hole through the bifurcation. Bearing bolt 38 extends through these holes. It will be noted that the bearing bolt 38 has a larger diameter through much of its length than the threaded end 35 where the nuts 40 are attached which results in additional strength. In operation, the entire weight of the sucker rod will be supported by this bolt, and strength is necessary. In most cases, the sucker rod will weigh more than a pound a foot. Therefore, in a five thousand foot

40 well, over five thousands pounds will be supported by the bearing bolt 38. Two nuts 40 are used to lock the bolt 38 securely as is customary.

Rigid arm 42 has flat top connection 44 which fits between the bifurcated portion of ear 36. It likewise has a hole through which passes the bolt 38. Thus, the rigid arm 42 is pivoted to the clamp 30. Roller 46 is connected by pivot bolt 48 between bifurcation 50 at the lower end of the rigid arm 42. The axis of the pivot

50 bolts 48 and 38 are parallel. The pivot bolt 48 is also secured in place by lock nut combination 52.

Elbow 54 projects from the lower portion of the rigid arm 42. The elbow 54 is L-shaped, having a horizontal portion at right angles attached to the rigid arm 42 and a portion thereafter extending parallel to 42 so that the end of the elbow is adjacent or opposite the roller 46. At the end of the elbow there is a hole therethrough for third pivot bolt 56. Lever 58 is pivoted to the elbow 54 by means of the pivot bolt 56. Lever 58 is pivoted to the elbow 54 by means of the pivot bolt 56. The lever 58 has lower portion 60 which extends below the pivot bolt and upper handle portion 62 above the pivot bolt. Bearing 64 is on a crook on the end of the lower portion 60 of the lever normal to the rest of the lever 58. The

60 axis of the bearing 64 is parallel to the pivot bolt 56 which is parallel to the other two pivot bolts. The bearing 64 has two rows of ball bearings.

Stop 66 projects from one side of the elbow so that rotation of the lever 58 toward the rigid arm 42 is limited. 70 Spring detent 68 extends through the elbow. Cup 70 is integral with the elbow 54 and has shaft 72 coaxial therewith. The shaft 72 is threaded on the end away

from the lever 58 and has nut 74 thereon to limit its travel toward the lever 58. The end of the shaft 72 toward the lever has rounded knob 76 thereon. Spring 78 acts between the back side of the cup 70 and the knob 76 to press the detent shaft into depression 80 on the lever.

Operation

With the lever 58 held parallel to the rigid arm 42 by the spring detent 68, the device is clamped to the polish rod 16. This clamping operation may be performed with the well in operation if the well is rather slow moving. In any event one man can easily stop the well and attach the clamp 30. Each half of the clamp 30 has segmental-cylindrical cavities which are correlative to the polish rod 16.

The clamp 30 is placed on the polish rod 16 so that the roller 46 (the outside surface of which forms a lower bearing surface) is about four inches below the top of the stuffing box 28 when the pump 8 is on bottom dead center. Then with the well pumping and the sucker rod reciprocating upon the down stroke the device is guided so that the roller 46 is seated on the top of the stuffing box 28. It will be noted that the distance of the top pivot bolt 38 is about three inches from the center of the polish rod 16. Therefore, the rigid arm 42 angles downward and toward the polish rod 16 so that the rigid arm 42 will not accidentally slip from the top of the stuffing box 28.

The device remains in this position until the horsehead 24 reaches the bottom of its stroke. As may be seen in FIG. 1, as the horsehead 24 continues its down stroke the cross bar 20 will slide down the polish rod 16 from the clamp 18. When the horsehead 24 gets to bottom dead center or slightly thereafter when it begins up, the top handle portion 62 of the lever 58 is rotated down and away from the rigid arm 42. The bearing 64 will pry against the stuffing box 28, and therefore move the roller 46 off the top of the stuffing box 28. This will therefore leave the sucker rod unsupported and allow the full weight of the sucker rod to drop until the clamp 18 contacts the cross bar 20. The free falling sucker rod will deliver considerable impact or jar when clamp 18 strikes cross bar 20 which will be transmitted on down the sucker rod to the valve 12 and therefore shake the valve 12 free of its stuck position. After the device has been tripped it will be in the position illustrated in FIG. 2.

If desired, upon the next down stroke of the pump the roller 46 may be positioned again on top of the stuffing box 28 and another impact delivered to the valve 12. Greater or lesser impacts may be delivered by placing the clamp 30 nearer or farther from the stuffing box 28.

It will be noted that there will be a slight impact delivered to the pump when the roller 46 contacts the top of the stuffing box 28. However, this will not be as great as when the sucker rod is allowed to fall free and be stopped short by the cross bar 20. This is because the horsehead has a slow, controlled rate of descent in normal operation.

Thus, I have provided a simple, safe, method of shaking a pump suitable for operation by one man operating alone. It will be understood that normally these pumps are operated by a single operator without other assistance.

I prefer to make the device from a high grade of steel but, of course, the material selected and the details of design will be well within the skill of those familiar with the art.

It will be apparent that the embodiment shown is only exemplary and that various modifications can be made in construction, materials, and arrangement within the scope of the invention as defined in the appended claims.

I claim as my invention:

1. In a well including a pipe extending deep within the

5 ground, a pump deep within the ground on the pipe, said pump having a valve to control the flow of fluid within the pump, a sucker rod connected to the pump, said sucker rod extending within the pipe to the surface of the ground, a stuffing box on top of the pipe to form a fluid tight seal between the pipe and the sucker rod, and means for reciprocating the sucker rod relative to the pipe; the improved means for shaking the valve comprising: a clamp clamped to the sucker rod above the stuffing box, a rigid arm pivoted to the clamp, a bearing surface on the lower end of the arm resting on the top of the stuffing box, an elbow attached to the arm extending adjacent the bearing surface of the arm on the stuffing box, and a lever pivoted to the elbow, a portion of said lever resting against the pipe; so that rotation of said lever forces the bearing surface from the top of the stuffing box allowing the sucker rod to fall free for a limited distance.

2. The invention as defined in claim 1 wherein the 10 lower portion of the rigid arm is bifurcated, a pivot bolt extending between the bifurcations, and a roller mounted for rotation on said pivot bolt, the outer surface of said roller being said bearing surface designated above.

3. The invention as defined in claim 1 with the addition 15 of a stop on the elbow limiting the rotation of the lever toward the rigid arm, a shaft extending through the elbow, a spring biasing said shaft toward the lever, and said lever having a depression therein opposite the shaft so that the lever is normally maintained by the 20 shaft in a position adjacent the stop.

4. The invention as defined in claim 1 wherein said 25 clamp has two portions which are hinged together, each of said portions having a segmental-cylindrical cavity therein, the cavity fitting on the sucker rod.

5. The invention as defined in claim 1 wherein said 30 arm angles toward the sucker rod from the clamp to the stuffing box.

6. An improved shaker for a well; said well including 35 a pipe extending deep within the ground, a pump deep within the ground on the pipe, said pump having a valve to control the flow of fluid from the pump, a sucker rod connected to the pump, said sucker rod extending within the pipe to the surface of the ground, a stuffing box on the top of the pipe to form a fluid tight seal between the pipe and the sucker rod, and means for reciprocating the sucker rod relative to the pipe; the improved shaker comprising: a clamp adapted to be clamped to the sucker rod above the stuffing box, a rigid arm pivoted to the clamp, a bearing surface on the extreme end of the arm from the pivot, said bearing surface adapted to rest on the top of the stuffing box, the arm having an elbow extending to the side and adjacent the bearing surface of the arm, and a lever pivoted to the elbow, a portion of said lever adapted to rest against the pipe so that in use rotation of the lever forces the bearing surface from the top of the stuffing box allowing the sucker rod to fall free for a limited distance.

7. The invention as defined in claim 6 wherein the 40 lower portion of the rigid arm is bifurcated, a pivot bolt extending between the bifurcations, and a roller mounted for rotation on said pivot bolt, the outer surface of said 45 roller being said bearing surface designated above.

8. The invention as defined in claim 6 with the addition 50 of a stop on the elbow limiting the rotation of the lever toward the rigid arm, a shaft extending through the elbow, a spring biasing said shaft toward the lever, and said lever having a depression therein opposite the shaft so that the lever is normally maintained by the shaft in a position adjacent the stop.

9. The invention as defined in claim 6 wherein said 55 clamp has two portions which are hinged together, each of said portions having a segmental-cylindrical cavity therein.

10. In a valve shaker comprising: a clamp, a rigid 60 arm pivoted to the clamp, said clamp being means for

attaching the rigid arm to a cylindrical rod, the arm having a bearing surface on the extreme end from the point pivoted to the clamp, the arm having an attached elbow extending adjacent the bearing surface, and a lever pivoted intermediate its ends to the elbow; so arranged and constructed that the clamp may be attached to a sucker rod of a deep well pump, the bearing surface resting on top of a stuffing box and the lever bearing against a pipe below the stuffing box, so that rotation of the lever will pry the bearing surface from the top of the stuffing box.

11. The invention as defined in claim 10 wherein the extreme end of the rigid arm is bifurcated, a pivot bolt extending between the bifurcations, and a roller mounted for rotation on said pivot bolt, the outer surface of said roller being said bearing surface designated above.

12. The invention as defined in claim 10 with the addition of a stop on the elbow limiting the rotation of the lever toward the rigid arm, a shaft extending through the elbow, a spring biasing said shaft toward the lever, and said lever having a depression therein opposite the shaft so that the lever is normally maintained by the shaft in a position adjacent the stop.

13. The invention as defined in claim 10 wherein said clamp has two portions which are hinged together, each of said portions having a segmental-cylindrical cavity

20
25
30

14. In a well including a pipe extending deep within the ground, a pump deep within the ground on the pipe, said pump having a valve to control the flow of fluid in the pump, a sucker rod connected to the pump, said sucker rod extending within the pipe to the surface of the ground, a stuffing box on the top of the pipe to form a fluid tight seal between the pipe and the sucker rod, and means for reciprocating the sucker rod relative to

the pipe; the improved means for shaking the valve comprising: a clamp clamped to the sucker rod above the stuffing box, said clamp having two portions which are hinged together, each of said portions having a segmental-cylindrical cavity therein, a rigid arm pivoted to one of said portions of said clamp, the lower extremity of the rigid arm being bifurcated, a pivot bolt extending from one bifurcation to the other, a roller mounted for rotation on said pivot bolt, the outer surface of said roller bearing on the top of the stuffing box, the arm angling from the clamp toward the sucker rod at the bearing, the arm having an elbow extending adjacent the roller, a lever pivoted to said elbow, a portion of said lever adjacent the pipe, a bearing mounted on the portion of said lever next to the pipe, said bearing resting against the pipe, a portion of the lever extending above the point where the lever is pivoted to the elbow, a stop on the elbow, said lever against the stop thus limiting the rotation of the lever toward the rigid arm, and a shaft extending through the elbow, a spring biasing said shaft toward the lever, said lever having a depression therein opposite the shaft so that the lever is normally maintained by the shaft in a position adjacent the stop; so arranged and constructed that rotation of said lever forces the bearing against the pipe thus forcing the roller from the top of the stuffing box, allowing the sucker rod to fall free for a limited distance.
